[57] CLAIM

The ornamental design for a combined container and closure, as shown and described.

DESCRIPTION

FIG. 1 is a perspective view of the combined container and closure showing our new design;

FIG. 2 is a side elevation view of the combined container and closure, the opposite side elevation being a mirror image thereof;

FIG. 3 is a side elevation view of the combined container and closure taken at 90° from FIG. 2, the opposite side elevation being a mirror image thereof;

FIG. 4 is a top plan view of the combined container and closure;

FIG. 5 is a bottom plan view of the combined container and closure;

FIG. 6 is a exploded side elevation view similar to that of FIG. 2, the opposite exploded side elevation being a mirror image thereof except for the continuous screw threading on the neck of the container;

FIG. 7 is an exploded isometric view of the combined container and closure;

FIG. 8 is a bottom plan view looking upward into the closure;

FIG. 9 is a top plan view of the container with the closure removed; and,

FIG. 10 is a cross sectional view through the closure.

The closure is shown separately in FIGS. 8 and 10 and the container is shown separately in FIG. 9 for clarity of illustration.

The portions of the closure that are not shown in the drawings or described in the specification do not form part of the claim design.
